MEANS FOR PRODUCING A TESTING THREAD

Paul Litty, Leipzig, Germany

Application June 12, 1937, Serial No. 147,970
In Germany June 13, 1936

9 Claims. (Cl. 19—98)

In order to obtain from any particular raw material a thread which can be tested as regards its spinning properties and its strength, it has hitherto been the practice to pass a large quantity of the raw fibrous material to be tested through the various machines required for its manufacture (carding engine, drawing frame, flier frame) to the spinning frame in the ordinary way of manufacture. As the normal machine requires a considerable quantity of raw material to fill it, that is to make it operate uniformly, the method was costly, inconvenient and time wasting, more particularly owing to the circumstance that the particular machine had to be withdrawn during this period from the ordinary course of manufacture. Moreover a considerable wastage of raw material resulted.

According to the invention it is possible, with a relatively small quantity of raw material, for instance 50 grams and less, to obtain in a very short time and without interfering with the course of manufacture, an accurate and reliable picture as to the properties of the raw material, which are most important for its future use, more particularly the strength of the thread, and thus from a number of samples of raw materials quickly to select the most suitable one. This presents the further possibility of weighing the waste and using it in judging.

According to the invention this is effected by presenting to a small carding engine the same small quantity of different fibrous materials, working it up on this machine to a web of certain length, passing the web again through the carding engine and making from it a uniform sliver, drawing this sliver on an adjustable drawing frame while ascertaining the correct cylinder position, and spinning it to a thread, the strength and uniformity of which is tested.

A device for carrying out the method is illustrated by way of example in the accompanying drawings, partly diagrammatically.

Figure 1 shows the device in side elevation, with some of the parts in section.

Figure 2 is a plan view of the device.

Figure 3 is a diagrammatic representation of details in side elevation and partly in section to a smaller scale.

Figure 3a shows some details in elevation and part section to a larger scale.

Figure 4 is a view of an intermediate product produced on the lines as shown in Figures 1 to 3.

Figure 5 shows a portion of Figure 3 with one part in another position, to the same scale as Figure 3.

The device for carrying out the method according to the invention consists substantially of a small carding engine A of special construction.

The small carding engine contains a feed conveyer band 1, which runs over guide rollers 1a and 1b, a feed trough 2 with a pressure applying roller 3, a licker-in 5, a main cylinder 6, a stripper roller 7, a doffer comb 8, a lap cylinder 9 and a weight roller 10. These parts correspond substantially to the parts of a large carding engine, with the difference that the dimensions are made so small that even quite small quantities of raw textile materials, such as 50 grams or less, completely cover these parts.

The following parts differ from those of a normal carding engine:

The feed conveyer band has laterally sliding bounding rails 11 for a purpose to be explained hereinafter. The main cylinder co-acts with several covers 13 set with pins, which are guided in a cover sector 12 and are held with an inner surface against the peripheral surface of the main cylinder yielding in an adjustable manner. The distance of the pin points of the individual covers from the pin points of the main cylinder is preferably greater at the feeding in place of the web, that is at 14, than at 15 (Figure 3). The cover sector is arranged so as to be easily removed, being preferably hinged at one end about a pivot 16. At the other end it rests on a holder 16a. Owing to this arrangement the cover sector can, for the purpose of easily cleaning the main cylinder and cover, be removed from the former, compare position 12a in Figure 3. Behind the doffer comb 8 a collecting funnel 17 is arranged so as to be capable of being moved into the path of the web coming from the doffer comb, for instance by means of a bow 18. Figure 3 shows it in the inoperative and Figures 1, 2 and 5 in the operative position.

Figure 3a shows the resilient and adjustable arrangement of the covers 13 in the cover sector 12, 13a being a spring and 13b an adjusting knob.

The drive of the various parts also differs from that of a normal carding engine and is arranged entirely to suit the particular requirements of a small machine for testing purposes. From a source of power next to the small carding engine, for instance an electric motor 19, by means of a belt 19a travelling over belt pulleys 20 to 22, the doffer motion, the main cylinder 6 and the licker-in 5 are driven. These belt pulleys are mounted on shafts 24, 23 and 25. From the shaft 25 of the licker-in there is driven by means of worm wheels a shaft 26 for imparting motion to the

roller 1a of the conveyer band and a shaft 21 for imparting motion to the stripper roller 7. A worm wheel 28 which transmits this motion, transmits the drive to a shaft 29 which through worm wheels 30, 31 drives the lap drum 9.

The roller 3 is journaled in a weight loaded lever 32.

Below the various rollers set with pins a slide-like collecting trough 33 with a handle 34 and an arresting device 35 is disposed. This collecting trough is divided up by partitions 36 and 37 into three compartments 38, 39, 40. The device according to the invention operates as follows:

A measured quantity of the raw textile material, for instance 50 grams, is laid on the feed band 1 after the guide rails 11 have been brought into an inner position 11a, see Figure 2. The raw material travels in the direction of the arrow D, is worked up on the carding engine, the web is taken off by the doffer comb 8 and is wound on to the lap cylinder 9. On this cylinder is formed a so-called lap 41 of a certain thickness, that is to say, in dependence of the periphery of the lap cylinder. After the small quantity of raw material therein has been completely worked up, the lap is cut open along a peripheral line of the lap cylinder as indicated at 42 in Figure 3. For this cutting open a groove 43 is preferably provided in the lap cylinder 9, see Figure 1.

30 This lap is placed again, as shown in Figure 4, on the feed band 1, after the guide rails 11 have been previously brought into an outer position, as during the operation of the carding engine the textile material has spread out. Before the small 35 carding engine is put in operation the collecting funnel 17 is placed in position (Figures 1, 2 and 5). By the said funnel the lap coming from the doffer comb is united and compacted into a sliver or band 44, that is indicated by line 45 (Figure 2).

40 Experience has shown, that a very small constructional form of carding engine of only about 1½ metres length, ½ metre breadth and ½ metre in height is ample for obtaining an accurate picture as to the particular raw material.

45 What I claim is—

1. A device for making a testing thread from a quite small quantity of fibrous material, for instance 50 gms., for ascertaining the spinning capacity and the properties of the fibrous material as regards strength, comprising a conveyer band, a feed trough, a licker-in, a main cylinder having a diameter less than twenty inches, a cover sector, a stripper roller, a doffer comb, a slotted lap cylinder, a collecting funnel capable of being moved into and out of the operative position in order to work up the lap a second time on the same carding engine and to form it into a sliver of very great uniformity.

2. A device for making a testing thread from a quite small quantity of fibrous material, for instance 50 gms., for ascertaining the spinning capacity and the properties of the fibrous material as regards strength, comprising in combination a conveyer band, a feed trough, a licker-in, a main cylinder having a diameter less than twenty inches, a plurality of separate adjustable covers set with disentangling members, a cover sector as the support for the separate covers, this cover sector being pivotally connected at one end and releasably supported at the other end, a stripper roller, a doffer comb, a slotted lap cylinder, a collecting funnel capable of being moved into and out of the operative position in order to work up the lap a second time on the same carding engine

75 and to form it into a sliver of very great uniformity.

3. A device for making a testing thread from a quite small quantity of fibrous material, for instance 50 gms., for ascertaining the spinning capacity and properties of the fibrous material as regards strength, comprising in combination a conveyer band, a feed trough, a licker-in, a main cylinder having a diameter less than twenty inches, a plurality of separate adjustable covers, set with disentangling members, the internal surface of these covers being positioned at the place of entry of the fibrous material farther from the peripheral surface of the said main cylinder than at the place where the fibrous material leaves, a cover sector as the support for the separate covers, the said cover sector being easily removable, a stripper roller, a doffer comb, a slotted lap cylinder, a collecting funnel capable of being moved into and out of the operative position in order to work up the lap a second time on the same carding engine and to form it into a sliver of very great uniformity.

4. A device for making a testing thread from a quite small quantity of fibrous material, for instance 50 gms., for ascertaining the spinning capacity and properties of the fibrous material as regards strength, comprising in combination a conveyer band, a feed trough, a licker-in, a main cylinder having a diameter less than twenty inches, a plurality of separate adjustable covers, set with disentangling members, the internal surface of these covers being positioned at the place of entry of the fibrous material farther from the peripheral surface of the said main cylinder than at the place where the fibrous material leaves, a cover sector as the support for the separate covers, the said cover sector being pivotally connected at one end and releasably supported at the other end, a stripper roller, a doffer comb, a 40 preferably slotted lap cylinder, a pivotally mounted bow member extending over the lap cylinder, a collecting funnel mounted on the said bow member in order to work up the lap a second time on the same carding engine and to form it into a sliver of very great uniformity.

5. A device for making a testing thread from a quite small quantity of fibrous material, for instance 50 gms., for ascertaining the spinning capacity and properties of the fibrous material as regards strength, comprising in combination a conveyer band, a feed trough, a licker-in, a main cylinder having a diameter less than twenty inches, a plurality of separate adjustable covers set with disentangling members, the internal surface of these covers being positioned at the place of entry of the fibrous material farther from the peripheral surface of the said main cylinder than at the place where the fibrous material leaves, a cover sector adapted to hold the individual covers in a yielding manner, the said cover sector being pivotally connected at one end and releasably supported at the other end, a stripper roller, a doffer comb, a slotted lap cylinder, a pivotally mounted bow member extending over the lap cylinder, a collecting funnel mounted on the said bow member in order to work up the lap a second time on the same carding engine and to form it into a sliver of very great uniformity.

6. A device for making a testing thread from a quite small quantity of fibrous material, for instance 50 gms., for ascertaining the spinning capacity and properties of the fibrous material as regards strength, comprising in combination a conveyer band, a feed trough, a licker-in, a main

5 cylinder having a diameter less than twenty inches, a plurality of separate adjustable covers set with disentangling members, the internal surface of these covers being positioned at the place of entry of the fibrous material farther from the peripheral surface of the said main cylinder than at the place where the fibrous material leaves, a cover sector as the support for the separate covers, the said cover sector being pivotally connected at one end and releasably supported at the other end, a stripper roller, a doffer comb, a slotted lap cylinder, a collecting funnel mounted on the said bow member extending over the lap cylinder, a collecting funnel mounted on the said bow member in order to work up the lap a second time on the same carding engine and to form it into a sliver of very great uniformity.

10

15

7. A device for making a testing thread from a quite small quantity of fibrous material, comprising in combination a conveyer band, a feed trough, a licker-in, a main cylinder having a diameter less than twenty inches, a plurality of separate adjustable covers set with disentangling members, the internal surface of these covers being positioned at the place of entry of the fibrous material farther from the peripheral surface of the said main cylinder than at the place where the fibrous material leaves, a cover sector as the support for the separate covers, the said cover sector being pivotally connected at one end and releasably supported at the other end, a stripper roller, a doffer comb, a slotted lap cylinder, a pivoted bow member extending over the lap cylinder, a collecting funnel mounted on the said bow member in order to work up the lap a second time on the same carding engine and to form it into a sliver of very great uniformity.

20

25

8. A device for making a testing thread from a quite small quantity of fibrous material, com-

prising in combination a conveyer band, a feed trough, a licker-in, a main cylinder having a diameter less than twenty inches, a plurality of separate adjustable covers set with disentangling members, a cover sector as the support for the separate covers, said cover sector being pivotally connected at one end and releasably supported at the other end, a stripper roller, a doffer comb, a slotted lap cylinder, a collecting funnel capable of being moved into and out of an operative position in order to work up the lap a second time on the same carding engine and to form it into a sliver of very great uniformity.

9. A device for making a testing thread from a quite small quantity of fibrous material, for instance 50 gms., for ascertaining the spinning capacity and the properties of the fibrous material as regards strength, comprising in combination a conveyer band, a feed trough, a licker-in, a main cylinder having a diameter less than twenty inches, a plurality of separate adjustable covers set with disentangling members, the internal surface of these covers being positioned at the place of entry of the fibrous material farther from the peripheral surface of the said main cylinder than at the place where the fibrous material leaves, a cover sector adapted to hold the separate covers in a yielding and adjustable manner, the said cover sector being pivotally connected at one end and releasably supported at the other end, a stripper roller, a doffer comb, a slotted lap cylinder, a pivoted bow member extending over the lap cylinder, a collecting funnel mounted on the said bow member in order to work up the lap a second time on the same carding engine and to form it into a sliver of very great uniformity.

PAUL LITTY.
